[57] **CLAIM**

The ornamental design for a combined flashlight and emergency light, as shown and described.

DESCRIPTION

FIG. 1 is a front elevational view of a combined flashlight and emergency light showing my new design;

FIG. 2 is a rear elevational view thereof;

FIG. 3 is a right side elevational view thereof, the left side elevational view being a mirror image thereof;

FIG. 4 is a top plan view thereof;

FIG. 5 is a bottom plan view thereof;

FIG. 6 is a perspective view from the front illustrating the rear arm in the extended position;

FIG. 7 is a perspective view from the rear also showing the rear arm in the extended position; and,

FIG. 8 is a perspective view from the front illustrating the rear arm in the closed position.
